UNITED STATES PATENT OFFICE.

FRANCIS JOHN WITTS, OF MANOR PARK, ENGLAND.

GUARD FOR EYEGLASSES.

1,153,000. Specification of Letters Patent. Patented Sept. 7, 1915.

Application filed February 18, 1914. Serial No. 819,453.

To all whom it may concern:

Be it known that I, FRANCIS JOHN WITTS, a subject of His Majesty the King of England, residing at 785 Romford road, Manor Park, in the county of Essex, Kingdom of England, have invented certain new and useful Improvements in Guards for Eyeglasses, of which the following is a specification.

10 This invention relates to improvements in rimless pince-nez fittings, and has particular reference to the form known in the trade as the "butterfly wing action", which form is illustrated in Figure 4 of the accompanying drawings.

15 The object of the invention is to provide a guard for nose glasses, having projections divided by a depression, the walls of which taper toward each other and in direction of the nose, the depression receiving and gripping the flesh to hold the glasses in position.

20 The invention also comprehends improvements in the details of construction and arrangement of parts which will be herein-25 after described and particularly pointed out in the claims.

Fig. 1 represents a strip of metal cut to the desired shape and size, suitable for making a pince-nez of average size; Fig. 2 is an 30 enlarged cross section of the plaquet, the nose of the wearer being shown in dotted lines; Fig. 3 shows the pince-nez viewed from above, with the spring opened ready for fixing in position on the nose. The

35 "butterfly wing action" is indicated by the inclination of the lenses g and g' to the plane of rest shown by the dotted line m m . Fig. 4 is an enlarged view of the plaquet a , and may represent the bare metal, finished 40 suitably smooth for contact with the skin, or it may represent the metal work of the plaquet insulated with cork, celluloid, tortoise shell or other suitable material as individual cases may require.

45 In carrying out the present invention the metal work forming the bridge of the pince-nez, *i. e.* that between d and d' Fig. 1 and the broadened strip at both extremities a and a' is rendered flexible by rolling or hammering. An acute angled groove c is impressed or cut into surface of the plaquets a and a' running throughout the length of the plaquet, and so shaped as to form a stop l and l' Fig. 4 with a rounded gripping edge

or surface l , rising to a plane slightly higher than that of the first similarly rounded gripping edge or surface h . The object of the edges and groove is that when placed in position on the nose, the flesh of the nose shall lightly embed itself before the edges and into the grooves and thereby act as a preventive to the falling off of the pince-nez.

55 The small tabs b and b' are drilled and suitably tapped to take the screws f and f' . The shaping and bending is next proceeded with; the bridge or spring j being curved outward and possibly slightly upward as a particular nose may require; at d and d' the metal is doubled back beneath, forming a complete return as far as h and h' Fig. 3, 65 where it is then bent downward at about right angles. The bending at d and d' is hammered, keeping the metal at that spot as far as possible in a vertical plane, and by this means the flexibility of the bridge piece 70 is extended gradually onward to the bends h and h' where to all practical purposes it disappears. From d and d' onward to h and h' the metal work gradually broadens and stiffens.

75 At o and o' the four drilled tabs are bent parallel to one another, and to the plane in which the lenses are to be mounted, and thus are made to form the clamps for the lenses, while the strips e and e' are curved into close 80 contact with the edges of the lenses, giving rigidity to the fixture of the lenses in their clamps.

85 At p and p' an abrupt return of the metal work upward forms the plaquets, the exact 90 tilt and adjustment of which can be arranged to suit as a case may need.

95 What I claim as my invention and desire to secure by Letters Patent of the United States is:—

1. A guard for eye-glasses, comprising two members, each member comprising an integral base portion from which projects a pair of gripping faces divided by a tapering depression, the side walls of which converge toward each other, and in direction of the base of the nose, the bottom wall of said depression terminating at the base, whereby movement of the members toward the front of the nose will force the flesh thereof into the tapering depression and hold the guard in position.

100 2. A guard for eye-glasses, comprising a

plurality of members, each member comprising a plurality of gripping faces divided by a central depression, one of said gripping faces being higher than the other of said faces.

5 In testimony whereof I have signed this

specification in the presence of two subscribing witnesses.

FRANCIS JOHN WITTS.
